(57) **CLAIM**

The ornamental design for a skin exfoliating device, as shown and described.

DESCRIPTION

FIG. 1 is a perspective view of a skin exfoliating device showing my new design;

FIG. 2 is another perspective view thereof;

FIG. 3 is a third perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof; and,

FIG. 10 is a perspective view of the skin exfoliating device on a cradle.

The broken lines in the drawings are for the purpose of illustrating portions of the skin exfoliating device that form no part of the claimed design. The broken lines showing a cradle in FIG. 10 are for the purpose of illustrating environment and form no part of the claimed design.
